GUIDED MISSILE

Otho E. McCrackin, St. Louis, Mo., assignor to the United States of America as represented by the Secretary of the Navy

Filed May 4, 1949, Ser. No. 2,421

Term of patent 3½ years

(Cl. D71—1)

FIG. 1

FIG. 2

FIG. 3

FIG. 4

FIG. 5

FIG. 6

Fig. 1 is a perspective view of the guided missile as it would appear when seen obliquely from above at the front, with the wings folded in a forward position prior to launching;

Fig. 2 is a side elevation of the guided missile in Fig. 1;

Fig. 3 is a perspective view of the guided missile as it would appear when seen obliquely from above and at the rear, in the condition shown in Fig. 1 prior to launching;

Fig. 4 is a perspective view of the guided missile as it appears in flight, the showing being as seen from the underside at the front;

Fig. 5 is a perspective view of the guided missile as it would appear when seen obliquely from above and at the rear but from a position different from that in Fig. 3, and

Fig. 6 is a side elevation of the guided missile in Fig. 4. The dominant features of my design for a guided

missile reside in the portions shown in full lines, said portions being characterized by the particular adjustable wings and the super structure in association with the fuselage, all as shown in the drawings.

What is claimed is:

The ornamental design for a guided missile, substantially as shown and described.
